UNITED STATES PATENT OFFICE.

CHARLES T. RASCHICK, OF ST. PAUL, MINNESOTA.

RESTAURANT CHECK.

Application filed October 6, 1922. Serial No. 592,725.

My invention relates to checks such as used in restaurants and the like, and has for its object to provide a check adapted to be severed in two portions, so that the lowest 5 number exposed upon the check indicates the amount of sale represented by the check.

Another object of the invention is to provide two columns of numerals for indicating the amount of sales, which columns are 10 adapted to be cut to cause the lowest numeral to occur in either of said columns.

Another object is to arrange the said numerals in two columns, so that by severing the check with a single straight cut across 15 the check that the lowest amount may be caused to fall in either column as desired.

A still further object is to arrange the numerals in each of the columns in alternative relation, so that the numerals in one 20 column occur adjacent the spaces between the numerals on the other column and vice versa.

The full objects and advantages will appear in the detailed description of my application and are particularly pointed out in the 25 claim.

In the drawings illustrating my application in one form:—

Figure 1 is a front view of my improved 30 check.

Figure 2 is a view similar to Fig. 1 showing a check severed to indicate an amount occurring in the right hand column.

Figure 3 is a view of a check similar to 35 Figure 2 severed to show the amount indicated in the left hand column.

In restaurant checks it is highly desirable to have the numerals indicating the amount of sales, large and conspicuous. In the type 40 of check where the same is severed to show the amount of sales by means of the lowest numeral indicated thereon, it has been customary to arrange the numerals consecutively in a single column and to sever the check 45 between the numerals. When numerals of a sufficient size of type have been employed to render the same suitably conspicuous, the check becomes so long that the same is awkward and cumbersome to handle.

50 My invention overcomes this difficulty by arranging the numerals in two columns, thereby practically cutting the length of the check in half. This permits of providing a properly proportioned check and of securing type which is sufficiently large to be easily read by the clerk and patron.

My improved check, which is shown in its entirety at A is printed on a suitable body 10 and is arranged with two columns of numerals 11 and 12. In column 12 numerals 60 13 are positioned which commence with 5 at the bottom of the column and range upwardly by tens to 95 at the top of the column. In a similar manner, numerals 14 positioned in column 11 commence at the bottom of the check 10 with 10 and range upwardly by tens to one dollar, (\$1.00), at the top of the check. The lowest numeral 5 indicated at 15 in column 12 lies above the stub 65 end 24 of check 10, as shown in Figure 1 70 and each of the succeeding numerals 13 is equally spaced from the same. In column 11, the numeral 10 indicated at 17 commences directly opposite the space 18 falling between numerals 5 and 15 in column 12, 75 which are indicated at 15 and 19. All of the succeeding numerals in column 11 which are indicated at 14 are also equally spaced from lowermost numeral 10 which is indicated at 17, said numerals being the same distance 80 apart as the numerals 13. This causes the numerals 14 in column 11 to fall directly opposite the spaces between the numerals 13 in column 12 and numerals 13 to fall opposite the spaces between the numerals 14 in 85 column 11. Between each of the numerals 14 and 13 is positioned a line 40 which serves to aid in severing the check at the required place. Above the two columns of numerals 11 and 12 are positioned the words, "Pay 90 smallest uncut number", as shown at 20 and above this wording, a number indicated at 21, which is the serial number of the check, and another number indicated at 22, which represents the waiter number. In addition 95 any such further information as may be required may be printed in the space 23 formed at the extreme upper edge of the check.

The stub of the check is shown at 24 and the various leaves of the check may be fastened through the stub end 24 by means of a staple 25 to form a pad, as in the ordinary manner.

In using the check, a cutter is provided, 100 having a shearing edge, which may be positioned transversely across both of the columns 11 and 12 at one time, and which may be moved along the said column to any position along the same. Such cutters are now in common use and will, therefore, not be described in detail in the application. By 105 tearing the check along the cutter the check 110

may be severed at any desired position. When it is desired to sever the check to indicate an amount in the right hand column, the check is severed directly below the 5 numeral which the check is intended to indicate. The check then on being severed shows the full amount of the numeral desired and shows the adjacent numeral in the other column cut in half. This will be 10 become apparent from Figures 2 and 3. Supposing it was desired to issue a check for 75¢, the check would then be severed along the line 40 immediately below the numeral 75, which is indicated at 41. At the same 15 time numeral 70 indicated at 42 would be cut in half. By complying with the instructions to pay the smallest uncut number, the amount to be paid would hence be 75¢ since the 70¢ mark has been cut in half.

20 In a similar manner, if it were desired to issue a 50¢ check, the check would be severed as shown in Figure 2 along one of the lines 40 immediately below numeral 50 which is indicated at 43 in column 11. In 25 this case, the numeral 45, which is indicated at 44, would be cut in half, so that the lowest uncut numeral would again be 50¢. In this manner, it can readily be seen that the check may be severed to indicate the amounts represented by any of the numerals in either column.

The advantages of my invention are ap-

parent. A bold faced conspicuous numeral can be used on the check which is easily legible to the clerk and patron. At the same 35 time, the check may be printed on a size of sheet which is convenient to handle and which would be economical in so far as the amount of paper required would be concerned. In addition, no confusion would 40 arise as to the amount to be paid as the instructions at the top of the check clearly specify to pay the smallest uncut number.

In accordance with the patent statutes I 45 have described the principles of operation of my invention together with the apparatus which I now consider to represent the best embodiment thereof, but I desire to have it understood that the construction shown is only illustrative and that the invention can be carried out by other means 50 and applied to uses other than those above set forth within the scope of the following claim.

I claim:—

A check having a plurality of numerals arranged in adjacent columns thereon and adapted to be transversely severed to indicate the amount payable at the line of severance thereof, said numerals being arranged in said columns in alternate arithmetical progression.

CHARLES T. RASCHICK.
